UNITED STATES PATENT OFFICE.

CHARLES H. TRASK, OF LYNN, MASSACHUSETTS.

BOOT OR SHOE HEEL TRIMMING MACHINE.

SPECIFICATION forming part of Letters Patent No. 357,739, dated February 15, 1887.

Application filed June 15, 1886. Serial No. 205,202. (No model.)

To all whom it may concern:

Be it known that I, CHARLES H. TRASK, of Lynn, in the county of Essex and State of Massachusetts, a citizen of the United States, 5 have invented a new and useful Improvement in Boot and Shoe Heel Trimming Machines, of which the following is a full, clear, and exact description, reference being had to the accompanying drawings, forming a part of this 10 specification, in explaining its nature.

The invention is an improvement upon that described in my application for Letters Patent of the United States, filed June 7, 1886, Serial No. 204,324; and it relates especially to 15 the heel trimmer or cutter, to the heel-rest, to the top-lift guide, and to the rand-cutter.

Referring to the drawings, Figure 1 is a view in end elevation of the upper part of the machine containing the features of my invention. 20 Fig. 2 is a view in front elevation thereof. Fig. 3 is a sectional view upon the line $x-x$ of Fig. 2. Fig. 4 is a view in elevation of the part forming the top-lift guide and connections, to which reference is hereinafter made. 25 Fig. 5 is a view in section upon the line $x-x$ of Fig. 3 in elevation of the parts in front of said line. Fig. 6 is a vertical section of the heel trimmer or cutter, rand-knife, rand guard or guide, and end of the operative shaft, illustrating a modified form of the invention. Fig. 30 7 is an elevation of the cutter in front. Fig. 8 is a rear elevation of the cutter. Fig. 9 is a view in elevation to represent the cutter and the relation which the top-lift rest and guide bears to it, and also representing the manner 35 in which the top-lift rest and guide is automatically moved and adjusted to conform to the varying curvature of the cutter as it is moved in and out. Fig. 10 is a plan view to further 40 illustrate this feature of my invention. Fig. 11 is a detail view of the same.

Referring to the drawings, A represents the sole-edge and welt-trimming cutters. They are like those described in my said application, are protected as therein described, and are supported upon a shaft substantially as 45 therein specified.

B is the shank-edge trimmer and welt-knife. They are like those described in said application, are mounted upon their operative shaft, and rotated and protected as therein specified.

C is the heel-trimming knife; but instead of being in two parts or sections, as described in said application, it is a solid cutter made from a solid block of metal, which is turned or 50 shaped to provide its circumference or surface with the desired curvature from the rear surface, c , to the front surface, c' . Of course the curvature or form of this circumference varies according to the style which it is desired the 55 edge surface of the finished heel shall have. This block has formed in it a hole, c^2 , for the reception of the shaft, and a keyway, c^3 . It also has cut from its surface or circumference inward the tangential recesses c^4 , which provide or form the cutting-edges c^5 of the knife. The openings or recesses c^4 are of sufficient 60 width to permit the cutting-edges to reach the heel edge and operate thereon, and also to provide a proper clearance for the chips or pieces 65 of stock removed from the heel; and these recesses are preferably further formed or shaped to increase in depth gradually from the front to the rear of the cutter, so that they shall be longer at the rear than at the front and 70 provide an inclined bottom or end, c^6 , upon which the chips or pieces of stock removed by the cutters shall be removed as the cutter is revolved, to be finally expelled at the rear of the cutter. The sections c^7 of the cutter, or those parts between the rear cutting- 75 edge and the entrance to the recess c^4 next adjacent, preferably have the same curve or shape—that is, they form parts of the circle upon which the cutter is struck. This cutter 80 possesses advantages in that it is strong, cheaply made, is easily sharpened, as it is only necessary to grind the surfaces c^8 on a flat wheel, and produces a very smooth and uniform result or finish.

The cutter is mounted upon its shaft C so as not to obstruct the passage or throwing off of the waste through the recesses c^4 . This is accomplished by forming the shaft with a shoulder, b , against which the cutter is held 90 in any suitable way. The length of the cutting-edge of the cutter preferably is longer than the longest cut which it is desired to make upon the heels, for which it is especially made; and in order that the heel may be properly 95 guided or presented to the cutter, and so as to obtain a longer or shorter cutting-surface 100

of the heel first presented to it. The heel is then turned upon the rest E, and as it is turned the length presented to the cutter varies and the top-lift guide and guard is automatically moved backward by the work and returned by the spring, the heel-rest moving with it, so that greater or less lengths of the cutting-surface of the cutter are brought into action at the proper time, the extent of such operating-surface being entirely governed by the length of the cut which it is desired to make on the heel.

The point or projection d^7 , which extends from the top-lift rest and guide-arm d^6 which bears against the cam or incline d^8 , is made adjustable in relation to the said arm d^6 , and I have shown it in the form of a screw, the rounded end of which forms the projection, as this is the simplest and easiest way by which this adjustment can be obtained. The inclined surface d^8 may be in the form of a recess or slot cut in the arm D^2 , as shown in Fig. 3, or it may be formed upon a block attached to the arm D^2 , as shown in Figs. 9, 10, and 11; and when this form of construction is used I prefer to give the block an adjustment in relation to the arm D^2 by pivoting it at h to the arm D^2 and by the adjusting-screw h' , which is arranged to bear against the end of the block h , to move it in and out, and in that manner govern the slope or inclination of the surface d^8 .

Many of the details of the construction shown and described are contained in my simultaneously-pending applications Nos. 205,203 and 205,204, and the parts and combinations claimed herein are not claimed in them, and the parts and combinations claimed in them are not claimed herein.

I reserve the right to make the cutter herein described the subject-matter of another application.

Having thus fully described my invention, I claim and desire to secure by Letters Patent of the United States—

1. In a heel-trimming machine, a top-lift rest and guard adapted to cover a portion of the surface of a rotary heel-cutter and to be moved by the work in one direction and by a

spring in a reverse direction, with a cam or 50 guide for governing the direction of said movement and maintaining it parallel to the cutting-edge of the cutter, substantially as specified.

2. In a heel-trimming machine, the combination of a rotary cutter with a top-lift rest and guide adapted to cover part of the surface of the rotary cutter and to be movable in one direction by the work and in a reverse direction by a spring, and a guiding surface or cam 5c for governing the direction of its movement in relation to the surface of the cutter, substantially as specified.

3. The combination of a rotary cutter, a top-lift guide, guard, and rest, D D', formed upon 65 the ring d , the arm d^2 , having a sleeve, d^3 , the post d^4 , the guide d^8 , and the springs d^9 d^{10} , substantially as described.

4. In a heel-trimming machine, the combination of a rotary cutter, a heel-rest, and a top-lift guide and rest simultaneously movable by means, substantially as described, in the same direction transversely the plane of rotation of the cutter and parallel with its cutting-edge, substantially as described.

5. The combination, in a trimming-machine, of a rotary cutter, a rest, E, movable transversely the plane of rotation of the cutter by the work in one direction and by a spring in the reverse direction, and a guide or cam for 80 maintaining the heel-rest at the same relative distance from the edge of the cutter as it is moved, substantially as described.

6. The combination of the rotary cutter C, the cutter-shaft C', the rand-guard, the rand-knife having the enlarged hole, and the bolt, stud, or other device for locking them against the cutter and to the shaft C', substantially as described.

7. The combination of the rotary cutter, the 90 rotary rand-knife having the enlarged hole g , and the rotary rand-guard, the rand-knife being movable in relation to the cutter and rand-guard, substantially as described.
